CLAIM

The ornamental design for a foldable windsock connector as shown and described.

DESCRIPTION

FIG. 1 is a top perspective view of a foldable windsock connector showing my new design;

FIG. 2 is a bottom perspective view thereof;

FIG. 3 is a left view thereof;

FIG. 4 is a right view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is a top perspective view thereof, showing the foldable windsock connector in a folded in a 45 degree of angle configuration;

FIG. 10 is a top perspective view thereof, showing the foldable windsock connector in a 90 degree of angle folded configuration;

FIG. 11 is an enlarged view of a portion labeled as "11" on FIG. 1; and,

FIG. 12 is an enlarged view of a portion labeled as "12" on FIG. 2.

The long dash-short dash broken lines depict enlargement boundaries that form no part of the claim. The evenly broken lines illustrate portions of the foldable windsock connector that form no part of the claimed design.
